UNITED STATES PATENT OFFICE.

FRANCIS L. DARRACH, OF PHILADELPHIA, PENNSYLVANIA.

HATCHWAY.

SPECIFICATION forming part of Letters Patent No. 376,864, dated January 24, 1888.

Application filed January 20, 1887. Serial No. 224,852. (No model.)

To all whom it may concern:

Be it known that I, FRANCIS L. DARRACH, a citizen of the United States, residing in the city and county of Philadelphia, State of Pennsylvania, have invented a new and useful Improvement in Self-Closing Doors for Hatchways, Skylights, &c., which improvement is fully set forth in the following specification and accompanying drawings, in which—

10 Figure 1 represents a top or plan view of self-closing doors for hatchways or skylights embodying my invention. Fig. 2 represents a vertical section in line $\alpha\alpha$, Fig. 1. Fig. 3 represents a side elevation of a modification 15 thereof.

Similar letters of reference indicate corresponding parts in the several figures.

My invention relates to improvements in automatic devices for closing the doors of hatchways; and it consists in providing the said doors with a prop formed of fusible material, having its ends connected with the adjacent parts of the door and frame thereof by non-fusible chains or equivalents, as herein set 25 forth and claimed.

Referring to the drawings, A represents the doors of hatchways, skylights, buildings, &c., of usual construction.

B represents a support or holder for holding 30 either door in open position.

In Figs. 1 and 2 the support is of the form of a prop or rod whose ends engage with the doors of a hatchway, &c., or of a prop or rod one end whereof engages with the door and 35 the other end engages with the floor or cross-beam thereof.

In Fig. 3 a support is shown as applied to the door of a building and another support as applied to a transom, window, or door, said 40 supports being of the form of props which engage with the door and window, respectively, and the frames thereof.

The prop in each case is made of fusible metal or material, whereby the same melts or 45 separates when subjected to the action of fire.

Attached to the prop are chains or connections C, of non-fusible metal or material, which are also attached to a proper part of the frame

of a hatchway, skylight, door or window frame, or other part of a building, for purposes to be 50 hereinafter stated.

It will be seen that when the doors are opened they are retained by the props. In the event of fire the props fuse or separate, due to the action of the heat or fire, and thus 55 lose their holding power, whereby the doors drop, thus closing the hatchway, skylight, &c., with which they are connected. The separated props are further controlled by the chains or connections C, whereby they remain suspended 60 without liability to drop to the floor beneath and injure persons thereon.

It is evident that the invention is serviceable for doors, shutters, &c., in roofs, &c., elevator-wells, light, air, or ventilator shafts, 65 and other places requiring protection of the order stated.

I am aware that it is not new to provide the door of a hatchway with a support formed of rope having a portion thereof fusible, neither 70 is it new to support the said door by hooks connected by a fusible ring, whereby in case of fire the hooks are separated, thereby causing the falling and closing of the door; but I am not aware that it is old to employ a prop 75 formed of fusible material and having its ends connected to the adjacent portions of the door and the frame thereof by chains or devices of a non-fusible character for the said purpose until the same was employed by me, as herein 80 claimed, the said device herein described being simple in character and inexpensive in cost.

Having thus described my invention, what I claim as new, and desire to secure by Letters 85 Patent, is—

A support for a door, &c., consisting of a fusible prop having connections of non-fusible material attached to its ends and to the adjacent portions of the frame, substantially as 90 described.

FRANCIS L. DARRACH.
